UNITED STATES PATENT OFFICE.

WALTER W. GUY, OF CHICAGO, ILLINOIS, ASSIGNOR TO COLONIAL FIREPLACE CO., OF CHICAGO, ILLINOIS, A CORPORATION OF ILLINOIS,

FIREPLACE.

1,024,508.

Specification of Letters Patent. Patented Apr. 30, 1912.

Application filed October 2, 1909. Serial No. 520,643.

To all whom it may concern:

Be it known that I, WALTER W. GUY, a resident of Chicago, in the county of Cook and State of Illinois, have invented certain new and useful Improvements in Fireplaces, of which the following is a full, clear, and exact description.

The invention relates to fire-places and more particularly to the mechanism for controlling the damper to regulate the draft in the throat of the fire-place.

In mechanism for operating dampers for fire-places, it has been found desirable in practice to have the mechanism disposed in the throat of the fire-place where it will be accessible for disconnection from the damper in event it becomes necessary to remove the damper for access to the chimney flue, or in cleaning the fire-place. When the damper-operating mechanism is accessibly disposed in the throat of the fire-place, it is desirable that it should be of such construction that its operation will not be affected by the smoke or heat passing through the throat and it is also desirable that this operating mechanism should be operable by a handle at the front of the fire-place, so that in order to adjust the damper, it will not be necessary to reach up into the throat of the fire-place to adjust the damper. The invention designs to provide improved damper-operating mechanism which may be operated by a handle at the front thereof, which may be accessibly disposed in the throat of the fire-place, so that disconnection may be made which permits the damper to be removed, and which will not be rendered inoperative by the heat and smoke passing through the throat of the fire-place, and which avoids cutting away the walls around the fire-place for connection to the damper.

In the drawings: Figure 1 is a sectional view of a fire-place embodying the invention. Fig. 2 is a section on a large scale of the damper operating mechanism. Fig. 3 is a section taken on line 3--3 of Fig. 2 and Fig. 4 is a plan of the runner which is operated longitudinally by the hand operated screw.

The fire-place comprises a floor 7, a back-wall 8, side-walls 6, an arch-wall 9, a chimney-flue 10 and a metallic dome 11 set into and supported by the back-wall and side-walls of the fire-place, as well understood in the art, the arch-wall being laid on the

lintel 12 of the dome. The rear wall 13 of the dome slopes downwardly from the top or peak and has an opening 14 therein. A damper 15, pivotally mounted as at 16, in lugs 17 on the dome, is adapted to close the opening and to regulate the draft of the fire-place, as well understood in the art.

In practice, it occurs that soot accumulates in the space in back of the damper and for the purpose of facilitating the removal of the soot from this place, the damper is usually constructed, so that it may be removed from the dome, the pivots 16 on the damper being held in open-slots 17a in the pivot-lugs 17 on the dome. The mechanism for adjusting the damper into different positions to close the opening 14 or to regulate the draft, comprises a shaft 18, which is journaled at its rear end in the back-wall 13 of the dome and at its front end in a bracket 19 secured to the lintel of the dome, the shaft extending transversely across the throat of the fire-place, through the lower portion of the arch-wall and to the front of the fire-place where it has secured thereto, an operating handle 20. To avoid friction between the arch-wall 9 and the portion of the shaft 18 which extends therethrough, a sleeve 21 is fitted to the front portion of the shaft so that the latter will be free to turn therein. A screw-sleeve 22 is mounted on the shaft, between the lintel and the back-wall of the dome, and is removably secured to shaft 18 by a cotter-pin 23 and is provided with a coarse screw 24. A runner 25 is mounted to travel longitudinally on the screw-sleeve and comprises side-lugs 26, a cross-rib 27 below the sleeve and a pair of cross-ribs 28 above the sleeve, these ribs extending transversely through the groove of the screw.

In practice, it has been found that heat and smoke sometimes cause the parts to become warped or covered with soot, so that if they are accurately fitted together, they would become inoperative as a result. Therefore, the runner is constructed as described, the ribs extending loosely across the groove of screw, and even if the screw-sleeve becomes warped, or covered with soot or rough, the runner will remain operative on the screw-sleeve and remove the soot from the screw when the latter is turned. A link-connection is provided between the runner and the damper which causes the

damper to be oscillated as the runner is shifted longitudinally on the screw-sleeve by rotation of the handle 20 and shaft 18. This link-connection consists of a double 5 link or a pair of members 29 and 30, the upper end of which are pivotally connected, by a pin 31, to a lug 32 on the damper 15. The lower ends of these link-members are 10 separated and extend respectively to the outer side of said lugs of the runner and are pivotally connected thereto by pins 33. As a result of this construction of the link-connection, it serves to hold the runner against rotation with the screw 24, so that when the 15 latter is turned, the runner will be caused to travel longitudinally on the screw-sleeve and operate the link-connection to shift the damper as desired. The runner will hold the link-connection and damper against movement except when the screw-sleeve is operated, so that locking mechanism for holding the damper in assigned position is unnecessary. To adjust the damper, it is only necessary to turn the handle 20, which will correspondingly turn shaft 18 and screw 24, which will cause the runner to travel forwardly or backwardly on the screw-sleeve according to the direction in which the handle is turned, and such shifting of the runner will correspondingly adjust the damper and hold it in assigned position.

The invention provides simple damper-operating mechanism which may be disposed in the throat of the fire-place, where it will be accessible in event it is desired to remove the damper or replace the operating mechanism. If it is desired to lift the damper out of the dome, this can be done upon removal of cotter-pin 23 and the withdrawal of shaft 40 18 forwardly out of its journals in the dome. The damper with the link-connection may be then lifted out of the dome, through opening 14, so that the space in the flue, back of the damper, will be accessible through said 45 opening, or the pivot-pin 31 may be disconnected from lug 32 to release the link which may then be swung downwardly with the runner, so that the damper will be free to be removed. In practice, it is customary to 50 mount the operating mechanism near one of the side walls of the fire-place, so that the damper, when the operating mechanism has been disconnected, may be tilted at such an angle that it can be removed through opening 14 and the space between the screw and the other side-wall of the fire-place. If it is

desired to clean the flue without removing the damper, the latter may be lifted forwardly and upwardly to raise pintles 16 out of slots 17^a, because the link-connection will 60 permit the damper to be thus lifted without disconnecting the damper-shifting mechanism.

The invention is not to be understood as restricted to the details shown and described, since these may be modified within the scope of the appended claims, without departing from the spirit and scope of the invention.

Having thus described the invention, what 70 I claim as new and desire to secure by Letters Patent, is:

1. In a fire-place, the combination of a dome, a damper movably mounted in the dome and mechanism for adjusting the 75 damper comprising a handle at the front of the fire-place, a screw operated by the handle, a runner longitudinally movable on the screw, a pivot at each side of the runner, and a link connection between the damper and 80 the runner comprising members pivoted to the damper and connected to the oppositely disposed pivots on the runner respectively.

2. In a fire-place, the combination of a 85 dome, a damper movably mounted in the dome and mechanism for adjusting the damper comprising a handle at the front of the fire-place, a transversely extending shaft to which the handle is secured, a sleeve 90 removably mounted on the shaft and having a screw thereon, a pin extending through the sleeve and the shaft for removably securing the shaft and sleeve together, a runner on the screw and a link-connection between the runner and the damper.

3. In a fire-place, the combination of a dome, a damper movably mounted in the dome and mechanism for adjusting the 95 damper comprising a handle at the front of the fire-place, and having its rear end supported by the dome, a sleeve mounted on the shaft, and having a screw thereon, a runner longitudinally movable on the screw and having side-lugs and separated cross-ribs for engaging the screw, and a double 100 link having its members pivotally connected to the side-lugs respectively and to the damper.
